Mr. O'Brien a design for Henry Phillips
Design for Stone Register

David Stuart & Jacob Beesley, of Philadelphia, Pa.
assignors to
William P. Cresson.

Letters Patent, No. 427. Dated, Dec. 3, 1857.

The schedule referred to in these Letters Patent & making part of the same.

To whom it may concern:

Be it known that we David Stuart and Jacob Beesley, all of the County of Philadelphia in the state of Pennsylvania have invented or produced a new and useful set of designs, which are intended to ornament a register & do hereby declare that the following is a full and exact description of the same.

Fig. 1, is intended to represent the inner front of Register, which is made fast in the frame, it being ornamented with a raised panel with a bar & rings attached as at a, a, a, a.

Fig. 2, represents the outer front which is ornamented with a raised panel in the centre of which is a succession of leaves & scroll work, as at b, b, b, b, running up & down. Outside the panel is some scroll work, as at c, c, c, c.

Fig. 3, represents the frame of the register very prettily ornamented with a succession of raised waisted carvings, as at d, d, d, d.

What we claim as our invention & desire to secure by Letters Patent, is, The ornamental design for a Register, as herein described and represented in the annexed drawings.
